COLLAPSIBLE TUBE COMPRESSOR

Harry Oscar, New York, N. Y.

Application December 4, 1937, Serial No. 178,036

5 Claims. (Cl. 221—60)

This invention relates to devices for dispensing the contents of collapsible containers, with special reference to thin walled, ductile metallic tubes, such as are commonly used as packages for a wide variety of plastic substances, like shaving creams, tooth pastes, artists' paints, et cetera, well known to the public.

Such collapsible tubes are ordinarily made with a firm discharge nozzle, provided with a removable cap, and are closed, after filling through the bottom, by seaming the lower, juxtaposed edges in such manner as to prevent leaks and the entrance of air.

In order to discharge a desired quantity of the substance in the tube pressure should be applied at the seamed end and gradually advanced as the contents become utilized.

Squeezing the tube by hand haphazardly is likely to cause its wall to break, and invariably leads to loss of the contents which remain therein after the distorted appearance of the tube indicates that it is empty.

While it is known that devices have been designed to engage the folded, seamed and closed end of such tubes, mostly in the form of a key on which the tube is progressively coiled as the contents are expelled, such devices have certain objectionable features, one of which is the difficulty of operation, due to lack of leverage on the turning handle; another noted objection is that such devices, by reason of their shape and size, seriously interfere with compact packing of the tubes in their customary cartons.

Having the matter in mind, it is an object of the invention to provide a compression device, applied at the closed end of the tube, and on which it may be progressively, tightly coiled, the device having a slideable handle element affording an effective grip when extended for use, and thereafter retracted to occupy no material space.

This and other advantageous purposes are accomplished by the novel construction and arrangement of few and simple parts hereinafter described and illustrated in the accompanying drawing, constituting a material component of this disclosure, and in which:

Figure 1 is a front elevational view of a conventional type of collapsible tube showing an embodiment of the invention as applied.

Figure 2 is a side elevational view of the same.

Figure 3 is a like view but showing the tube as partially coiled and the contents escaping from the nozzle.

Figure 4 is a fragmentary sectional view taken

approximately on line 4—4 of Figure 2, but showing the lever grip as in position for operation.

Figure 5 is an end elevational view thereof.

Figure 6 is a transverse sectional view taken on line 6—6 of Figure 4.

Figure 7 is a fragmentary front view of a modification in construction in which the end device is removably engaged with the tube.

Figure 8 is an end elevational view thereof.

Figure 9 is a perspective view of the same.

Figure 10 is a sectional view, similar to Fig. 4, but showing a modification in construction.

Referring in greater detail to the drawing, the numeral 15 designates a conventional type of collapsible tube, having an outlet or discharge 15 nozzle 16, provided with a removable cap 17.

The tube is usually filled with plastic material entered through the bottom, then open and cylindrical in shape; after filling this lower end is flattened, presenting two opposed sides which are pressed firmly into engagement, as at 18, seamed in the usual manner to produce a hermetically sealed joint extending straight across the tube approximately, at its center, and may be turned upon itself to form a hem-like terminal.

The invention comprises a pair of thin, but rigid, plates 20, adapted to clamp the seamed elements 18 between them and are securely held thereon by indentations 21 whereby the seam is firmly gripped.

As will be seen, the upper edges of the clamp plate extend only to the flattened portion of the seam, while their lower edges are integrally connected by a tubular sheath 22, which, like the clamp plates, extend the full length of the seamed portion of the tube 15.

The sheath 22 is provided with a straight narrow slot 23, preferably in its wall, opposite the clamp plates, and slideable in the sheath is a rod 25 having intermediate its length a flattened nodule 26, struck outwardly to slidably engage in the slot, which limits its sliding movement and also transmits rotary motion to the sheath when the rod is turned.

The rod 25 is bifurcated at one end portion 45 and is pivoted on a pin 27. Set therein is a lever-like handle 28 having a head 29 of greater diameter than the interior of the sheath, and by which the rod may be withdrawn, the handle turned on its pivot and thereafter used to rotate the rod and the sheath in curling the compressible tube thereon, these elements acting as a winding mandrel.

When the element 28 is turned to extend into the rod, the head 29 only reaches beyond the de-

vice, but when the rod is drawn outwardly, and the handle turned at a right angle, an effective leverage is obtained whereby the tube may be readily compressed and its contents forcibly delivered at the nozzle 16, as indicated in Figure 3.

In the modification, shown in Figures 6, 7 and 8, the tube seam 18 is enclosed between plates 30 one of which, in this case, is provided with inner-reaching clips 31 slidable along depressed longitudinal trackways in the seam.

The plates are integrally connected at their lower edges by a tubular sheath 32 in which is a slidable rod 33 provided with a handle 34 by which the mandrel, thus formed acts as a nucleus for the collapsible tube as it is wound thereon.

In this type of clamp coiling mandrel the sheath is reduced at one end to receive the head of the rod 33, turned into the position shown in Figs. 7 and 8, to avoid occupying excess space in the carton in which the tube is packed.

In the modified form seen in Figure 10, the same arrangement of clamp plates is used, but the sheath includes two portions 40 and 41, of different cross sectional area, the smaller 40 being receptive of a rod 42 having an enlarged square rear portion 43, fitting the section 41, thereby limiting the withdrawal of the rod and providing for rotation.

30 The lever 44, pivoted in the reduced portion of the rod, is provided with an enlarged head 45 as previously described.

It will be understood that the rods and sheaths in any of the views shown may be of any cross section, as round, square or otherwise, and of such dimensions as are suited to their purpose.

While certain preferred embodiments of this device have been shown and described, it will be understood that changes in the form, arrangements, proportions, sizes and details thereof may be made without departing from the scope of the invention as defined in the appended claims.

Having thus described the invention, what is

claimed as new and desired to secure by Letters Patent, is:—

1. A collapsible tube compressor comprising rigid plates secured on opposite sides of the closed end of the tube, a sheath integrally connecting the lower edges of said plates, a slotted rod limitedly slidable in said sheath, and a finger grip lever pivoted in the slot of said rod. 5

2. A collapsible tube compressor comprising clamp plates on the closed end of the tube, a 10 sheath connecting the bottom edges of said plates, a coiling key slidable in said sheath, and means limiting the inward and outward movement of said key, said means also operative to transmit rotary motion. 15

3. A collapsible tube compressor comprising a metal blank shaped to produce a straight cylindrical sheath having a longitudinal slot in the wall thereof intermediate its ends, said sheath having a lengthwise opening, plates integral with 20 the edges of the sheath opening and extending in parallel to receive the closed end of a collapsible tube therebetween, means for rigidly securing said plates to the tube end, a rod slidable in said sheath, said rod bifurcated at one 25 end, a finger grip pivoted in the bifurcated end, said grip having a circular head at least equal to the outer diameter of the sheath, and a lug on said rod operable in the slot of said sheath.

4. A collapsible tube compressor comprising a 30 clip, a cylindrical sheath combined with said clip, a rod telescopically contained in said sheath, said rod limited in its movement, a lever-like handle pivoted in said rod, and a head on said handle by which the rod may be drawn outwardly and retracted. 35

5. A collapsible tube compressor comprising a clip fixed on the sealed end of the tube, a cylindrical sheath combined with said clip, a handle slidable in said sheath and means to limit 40 longitudinal movement of said handle.

HARRY OSCAR.
